OUTBOARD MOTOR ATTACHMENT

Leroy A. Daly, Chicago, Ill.

Application July 21, 1939, Serial No. 285,671

9 Claims. (Cl. 9—8)

This invention relates to an attachment for use upon so-called outboard or portable marine motors.

It has been found in the use of outboard motors which are attached to row boats, canoes and other small boats, that a considerable number of such motors are lost in lakes, rivers and other relatively small bodies of water where they are used due to the fact that such outboard motors are occasionally torn loose or otherwise become dislodged from the rear wall or gunwale or other parts of the boats on which they are mounted and hence sink and are lost.

It has also been found, in this connection, that while it is possible to recover an outboard motor from the bottom of the usually small lakes, rivers and the like bodies of water on which they are used, if the lost motor can be located, it is a difficult matter to locate such a lost motor once it has sunk to the bottom of a lake, river or other relatively small body of water on which outboard motors are used.

Accordingly, it is a primary object of the present invention to provide a relatively simple, inexpensive and efficient device for attachment to an outboard motor and by means of which such a motor may readily be located in the event that it becomes torn loose or otherwise separated from the boat on which it is mounted and sinks to the bottom of the lake, river or other relatively small body of water on which outboard motor boats are commonly used.

Another object of the present invention is to construct the new device in such a manner that it may be used not only to locate a lost or sunken outboard motor but also to retrieve or recover the same.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a view partly in section and partly in side elevation showing a typical embodiment of the present invention attached to an outboard motor which, in turn, is shown as being attached to the rear wall of a small boat;

Fig. 2 is a fragmentary top plan view, partly in section, on line 2—2 in Fig. 1;

Fig. 3 is a view partly in vertical section and partly in side elevation; and

Fig. 4 is a view on line 4—4 in Fig. 3, partly in section and partly in side elevation.

A preferred and typical embodiment of the present invention is illustrated in the drawing, is therein generally indicated at 10, and is shown as being used in conjunction with an outboard motor 11 of conventional design and which motor 11 is shown as being attached, by suitable clamping means 12 to the rear or stern wall or gunwale 13 of a small boat 14, only part of which is shown.

The present invention contemplates the provision of a floatable or buoyant marker which will float upon the surface in the event that, for any reason, the outboard motor 11 becomes dislodged from its mounting on the rear wall or gunwale 13 of the boat 14 and sinks to the bottom of the lake, river or other usually small body of water on which outboard motors and outboard motor boats are commonly used.

To this end I provide a small and preferably spherical floatable or buoyant marker in the form of a body of cork or other buoyant material 15 which is normally housed in a container or casing which is generally indicated at 16. The casing 16 is relatively very small compared to the size of the outboard motor 11, as may be seen by an examination of Fig. 1, it is preferably made of aluminum or other non-corrosive metal, and includes a body 17 which is generally cylindrical in shape. The upper end of the body 17 of the casing 16 is closed by an end wall 18 and the casing 16 has an open lower end or bottom 19 which is normally closed by a closure member 20. The closure member 20 is removably mounted on the open lower end portion or bottom 19 of the body 17 of the casing by means of an annular flange 21 which is formed thereon and which has a tight slidable press fit and embraces the lower end portion of the wall of the body 17 of the casing 16.

Extending through a diametrically extending opening 22 which is formed in the body of the floatable or buoyant marker 15 is an end portion 23 of a flexible element or cord 24 which is normally wound or coiled in the form of a cylindrical body which is normally housed in the body 17 of the casing 16; the end portion 23 of the cord or flexible element 24 being secured to the top of the floatable marker 15 in any suitable manner as, for example, by means of a knot 25 which is formed in the cord 24 at the top of the floatable marker 15, as shown in Fig. 3, or otherwise.

The lower end portion 26 of the flexible element or cord 24 is attached to an eye or eyelet 27 which is formed as a part of an attaching member 28 which is preferably formed as a metal

stamping, this member 28 being soldered or otherwise secured in an opening 29 which is formed in the closure member 20 and has a water tight connection therewith.

The member 28 also includes a second eye or eyelet 30 which is arranged outside of or below the closure member 20, rather than inside the same as is the eyelet 27, and one end portion of a flexible attaching element in the form of a chain 31 is attached to this eyelet 30, the other end portion of this flexible element or chain 30 being attached to a suitable part of the motor 11 as, for example, to a ring 32 which is slidably mounted upon the vertically-extending motor-supporting shaft 33 of the motor 11.

Attached to and carried by the top wall 18 of the casing 16 is an eye bolt 34 which extends through an eye or opening 35 which is formed in a wall 36 of a clamping bracket 37 by means of which the casing 16 is removably attached or clamped to the rear wall 13 of the boat 14.

The clamping bracket 37 is preferably formed of one piece of metal and includes a U-shaped part (Fig. 3) which provides a pair of spaced parallel clamping jaws 38 and 39, and carried by the clamping jaw 39 is an adjustable clamping device or screw 40, of conventional design, and which is adapted to clampingly engage the rear wall 13 of the boat 14.

Operation

The operation and manner of use of the present invention are as follows:

If the present invention is to be used merely as a marker for locating a lost or sunken motor in a relatively small body of water such as a small lake or river, the cord 24 may be made of relatively light material having a low tensile strength, whereas if the new device is to be used not only for locating but also for retrieving a lost motor the cord or flexible element 24 may be formed of cotton material which is preferably about $\frac{1}{2}$ " in diameter and has a tensile strength of about ninety (90) pounds which is more than sufficient to support the average outboard motor since such motors usually weigh not in excess of about fifty (50) pounds.

The floatable marker 15 is normally disposed in the upper part of the body 17 of the casing 16 and the cord or flexible element 24 is normally wound into the form of a cylindrical coil or body of the same which is arranged in the body 17 of the casing 16, below the floatable marker 15, and the closure member 20 is normally mounted on the lower end portion of the body 17 of the casing 16 so as to close the open lower end thereof, as shown in Fig. 3, and thus provide a water tight casing 16.

With the parts thus assembled, one end portion of the flexible element or small chain 31 may be attached to any suitable part of the outboard motor 11, as by means of a ring 32 which is attached to one end portion of the flexible element or chain 31, this ring 32 being slidably mounted on the vertically extending motor-supporting shaft 33 of the motor 11 (Fig. 1). The casing 16 may then be suspended vertically from its clamping and supporting bracket 37 at the rear of the rear wall 13 of the boat 14, the bracket 37 being clamped to the rear wall 13 of the boat 14 by the clamping jaw 38 and the adjustable clamping device or screw 40 (Fig. 3).

Accordingly, when the parts of the new device have thus been assembled, and the device mounted in the manner hereinbefore described and as

shown in the drawing, if and when, for any reason, the outboard motor 11 is torn loose from, or for any reason, becomes dislodged from its mounting upon the boat 14, as occasionally happens, and drops into the lake, river or other relatively small body of water on which such motors are commonly used, the weight of the falling or sinking motor will slide the closure member 20 off from the lower end portion of the body 17 of the casing 16 and as the motor 11 and the closure member 20 sink the flexible element or cord 24 will gradually pay out or unwind from the coil or cylindrical form in which it is normally wound so that when the cord 24 has been completely paid out or unwound it will pull the floatable marker 15 out of the body 17 of the casing 16, through the open end 19 thereof, and into the water.

It will be noted, in this connection, that the cord or flexible element 24 is made long enough to enable it to extend from the surface to the bottom of small lakes, rivers and like small bodies of water on which outboard motors are commonly used.

It will be seen, therefore, that when the motor 11 and the closure member 20 sink, and the cord 24 pays out or unwinds and withdraws the floatable marker 15 from the body 17 of the casing 16, the marker 15 will, by reason of its buoyant nature, float upon the surface of the river, lake or other relatively small body of water in which the outboard motor 11 has sunk and hence the marker 15 will thus indicate or mark the position of the sunken motor 11.

It will be noted, in this connection, that if the device is intended to be used only as a marker, and the cord 24 is not heavy or strong enough to lift the sunken motor, the latter may, of course, be recovered in other ways as, for example, by the use of a rope or chain having grappling hooks attached thereto, whereas the cord or flexible element 24 may also, as hereinbefore stated, be made strong or heavy enough to lift the sunken motor 11, if the lifting operation be done carefully and without sudden or violent pulls on the line 24.

It has been found to be impractical for the user of the new device to attempt to rewind or coil the flexible element or cord 24 after the latter has once been paid out in use, so that when the sunken motor has been recovered, the end portions 23 and 26 of the flexible element or cord 24 may be detached from the floatable marker 15 and the eyelet 27 and a new cord or flexible element in the form of a cylindrical coil or body thereof substituted in its place and its end portions attached to the floatable marker 15 and the eyelet 27. The new or replacement cord 24, together with the float 15, may then be inserted into the body 17 of the casing 16 through the open end 19 thereof, whereupon the closure member 20 may be replaced in position of use upon the open end portion 19 of the casing 16 so as to close the same, thus rendering the device again ready for use.

It will be seen, therefore, from the foregoing description, in conjunction with the accompanying drawing, that the present invention provides a relatively simple, inexpensive and efficient device for attachment to an outboard or small portable marine motor and boat and by means of which such an outboard motor may readily be located or located and recovered, as hereinbefore explained, if, for any reason, it becomes dislodged from the boat on which it is normally

mounted and sinks in a relatively small lake, river or other relatively small body of water on which outboard motors and outboard motor boats are commonly used.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

I claim:

1. In a device of the character described, the combination of: a casing including a body having an opening formed therein, a closure member normally mounted upon the said casing body so as to close the said opening therein but said closure member being adapted to be withdrawn from the body of the said casing so as to uncover the said opening therein, a floatable member normally disposed in the said body of the said casing, but adapted to be withdrawn therefrom through the said opening therein, a flexible element having its major portion normally wound into a coil and said coil being normally arranged in the said body of the said casing, said flexible element having a portion attached to the said floatable member and having a portion thereof attached to the said closure member, a second flexible element having a portion thereof attached to the said closure member and having a portion provided with means for attaching it to an outboard motor, and means for attaching the body of the said casing to an outboard motor boat.

2. The device which is defined in claim one (1) and in which the body of the said casing is generally cylindrical in form and has an open lower end, and in which the said closure member has an annular flange which is slidably mounted on the lower end portion of the said body of the casing by means of a tight or press fit therewith so as to close the said open lower end thereof.

3. The device which is defined in claim one (1) and in which the body of the casing is generally cylindrical in form and has an open lower end, and in which the said closure member has an annular flange which is slidably mounted on the lower end portion of the body of the casing by means of a tight or press fit therewith so as to close the said open lower end of the body of the said casing, and in which the means for attaching the body of the said casing to an outboard motor boat is designed and adapted to suspend the body of the said casing in a substantially vertical position from, and rearwardly of, the rear or stern wall of said outboard motor boat.

4. The device which is defined in claim one (1) and in which the body of the casing is generally cylindrical in form and has an open lower end, and in which the said closure member has an annular flange which is slidably mounted on the lower end portion of the body of the casing by means of a tight or press fit therewith so as to close the said open lower end of the body of the said casing, and in which the means for attaching the body of the said casing to an outboard motor boat is designed and adapted to suspend the body of the said casing in a substantially vertical position from, and rearwardly of, the rear or stern wall of said boat, and in which the said floatable member is disposed above the said coil in the body of the said casing.

5. In a device of the character described, the

combination of: a casing including a body having an opening formed therein, a closure member removably mounted on the body of the said casing so as normally to close the said opening therein, a floatable member normally arranged in the body of the said casing but adapted to be withdrawn therefrom through the said opening therein, a flexible element having its major portion normally wound into a coil and said coil being normally disposed in the body of the said casing between the said opening therein and the said floatable member, said flexible element having a portion attached to the said floatable member and having another portion attached to the said closure member and means for connecting the closure member with an outboard motor.

6. In a device of the character described, the combination of: a casing including a body having an opening formed therein, a closure member removably mounted on the body of the said casing so as normally to close the said opening therein, a floatable member normally arranged in the body of the said casing but adapted to be withdrawn therefrom through the said opening therein, and a flexible element having its major portion normally wound into a coil and said coil being normally disposed in the body of the said casing between the said opening therein and the said floatable member, said flexible element having a portion attached to the said floatable member and having another portion attached to the said closure member, and a second flexible element arranged outside of the said casing and having a portion thereof attached to the said closure member and provided with means for attaching it to an outboard motor.

7. The device defined in claim five (5) in which the body of the said casing is generally cylindrical in form and in which the said opening therein is formed in the lower end thereof, and in which the said flexible element is normally wound into the form of a substantially cylindrical body or coil thereof.

8. In a device of the character described, the combination of: a casing including a body having an opening formed therein, a closure member removably mounted on the body of the said casing so as normally to close the said opening therein, a floatable member normally arranged in the body of the said casing but adapted to be withdrawn therefrom through the said opening therein, and a flexible element having its major portion normally wound into a coil and said coil being normally disposed in the body of the said casing between the said opening therein and the said floatable member, said flexible element having a portion attached to the said floatable member and having another portion attached to the said closure member, a second flexible element arranged outside of the said casing and having a portion thereof attached to the said closure member and having means for attaching it to an outboard motor, and means including a clamping device for attaching the body of the said casing to an outboard motorboat.

9. In a device of the character described, the combination of: a casing including a body having an opening formed therein, a closure member removably mounted on the body of the said casing so as normally to close the said opening therein, a floatable member normally arranged in the body of the said casing but adapted to be withdrawn therefrom through the said opening therein, and a flexible element having its major portion normally wound into a coil and said coil be-

ing normally disposed in the body of the said casing between the said opening therein and the said floatable member, said flexible element having a portion attached to the said floatable member and having another portion attached to the said closure member, a second flexible element arranged outside of the said casing and having a

5 portion thereof attached to the said closure member and having means for attaching it to an outboard motor, and means including a clamping device for suspending the body of the said casing from the rear or stern wall of an outboard motor-boat.

LEROY A. DALY.
